(57) **CLAIM**

The ornamental design for a desk as shown and described.

DESCRIPTION

FIG. 1 is a top, front perspective view of a desk showing my new design;

FIG. 2 is a top, rear perspective view thereof;

FIG. 3 is a bottom, front perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

The broken lines depict portions of the desk that form no part of the claimed design.

1 Claim, 9 Drawing Sheets
